[57] CLAIM

The ornamental design for a milk requirement indicator, substantially as shown and described.

DESCRIPTION

FIG. 1 is a front elevational view of a milk requirement indicator embodying our design;
FIG. 2 is a rear elevational view of the milk requirement indicator depicted in FIG. 1;
FIG. 3 is a top plan view of the milk requirement indicator shown in FIG. 1;
FIG. 4 is a bottom plan view from the other end of the milk requirement indicator; and
FIG. 5 is a side elevational view of the milk requirement indicator as depicted in FIG. 1.
The indicia are shown in broken lines for illustrative purposes only.

FIG. 1

FIG. 2

FIG. 3

FIG. 4

FIG. 5

UNITED STATES PATENT OFFICE
CERTIFICATE OF CORRECTION

Patent No. Des. 246,335 Dated November 8, 1977

Inventor(s) John Leslie Hopkins, Arthur Holmes

It is certified that error appears in the above-identified patent and that said Letters Patent are hereby corrected as shown below:
